CLAIM

We claim the ornamental design for a water misting fan with enlarged sprayer actuator, as shown and described.

DESCRIPTION

FIG. 1 is a front perspective view of the water misting fan with enlarged sprayer actuator showing our new design; FIG. 2 is a perspective view taken from the left bottom front corner of the water misting fan with enlarged sprayer actuator;

FIG. 3 is a right side view thereof;

FIG. 4 is a left side view thereof;

FIG. 5 is a front view thereof;

FIG. 6 is a rear view thereof;

FIG. 7 is a top plan view thereof; and,

FIG. 8 is a bottom view thereof.
